UNITED STATES PATENT OFFICE.

PAUL MASCHER, OF EAST PALESTINE, OHIO, ASSIGNOR OF ONE-HALF TO
PATRICK DOLAN, OF EAST PALESTINE, OHIO.

POOL-TABLE ATTACHMENT.

No. 806,158.

Specification of Letters Patent.

Patented Dec. 5, 1905.

Application filed November 15, 1904. Serial No. 232,849.

To all whom it may concern:

Be it known that I, PAUL MASCHER, a citizen of the United States, residing at East Palestine, in the county of Columbiana and State of Ohio, have invented a new and useful Pool-Table Attachment, of which the following is a specification.

This invention relates to attachments to pool-tables or other tables having pockets to receive balls employed in the playing of the game, the object being to provide a raceway to receive the balls from the pockets and conduct them to the end of the table.

A further object of the invention is to provide a device of the character mentioned which may be readily applied to any ordinary pool-table without requiring any change or modification in the construction of the table itself.

The invention consists of a track or raceway, in combination with novel means for securing the track or raceway to a table.

The invention further consists in the novel means hereinafter described for supporting the balls at the end of the table after they have been conducted there through the track or raceway.

In the drawings, Figure 1 is a view in perspective of a pool-table with my improvement applied thereto. Fig. 2 is a vertical section through one of the pockets of the table, showing the means for supporting the trackway. Fig. 3 is a view in perspective of one of the supporting devices of the trackway.

The reference-numeral 1 designates a pool-table having the usual side and corner pockets 2.

My improved attachment comprises a track or raceway 3 of approximately semicircular form in cross-section and extending along the sides and across the end of the table in position to receive the balls as they drop from the pockets. The track or raceway is arranged at such an inclination toward the front or starting end of the table as will direct the balls by gravity to that end.

The track or raceway is supported at points between the pockets by bracket-arms, each comprising a hook portion 4 to embrace the under side of the trackway, and a horizontal arm 5, secured by screws or other fastening devices to the under side of the rail of the table. In addition to these bracket-arms the

track or raceway is supported by the novel devices shown in Figs. 2 and 3, each comprising a substantially cylindrical body portion 6, having an intermediate portion thereof reduced and extended into the adjacent pocket of the table and its lower end provided with inwardly-projecting perforated arms 7, adapted to engage the opposite sides of the track or raceway, there being suitable clamping-screws 7' threaded in the perforations of said arms for engagement with the raceway, as shown.

To apply my attachment to an ordinary pool-table having the usual network pockets, the lower ends of the pockets are cut off to permit the cylindrical-shaped supporting devices to be inserted.

The trackway 3 is preferably lined with any suitable fabric to render it comparatively noiseless, and the cylindrical-shaped body portions 6 of the supporting devices are also preferably lined for the same purpose.

On the front or starting end of the table the raceway 3 is formed with an extension 8, which provides a rest or support for the balls employed in the game, said extension being of sufficient size to accommodate all of the balls employed in a game at the same time.

It will be apparent that my improvement is adapted for attachment to any ordinary pool-table by simply cutting off the ends of the pockets of the table and then applying the supporting-brackets and raceway, the latter being secured to the brackets by screw-bolts or other fastening means.

It will be obvious that any pieces of chalk falling through the pockets may be readily removed from the trackway, inasmuch as the latter is open on its upper side throughout its length.

While I preferably employ sheet metal in the construction of the trackway, I would have it understood that the invention comprehends all such variations in material, size, and form as may be embraced within the scope of the invention.

Having thus described the invention, what I claim is—

1. The combination with a pool-table, of a track or raceway, and a supporting device comprising a substantially cylindrical-shaped body portion having an intermediate portion thereof reduced and extended into the pocket

of the table and its lower end provided with inwardly-projecting arms adapted to engage said raceway.

2. The combination with a pool-table, of a track or raceway, and a supporting device for the raceway comprising a substantially cylindrical-shaped body portion having a reduced neck the walls of which are curved outwardly and adapted to engage the pocket of the table.

3. The combination with a pool-table, of brackets secured to the table at points between the pockets, a track or raceway secured to the brackets, supporting devices each comprising a substantially cylindrical-shaped body portion the upper end of which is extended within the pocket and the lower end thereof provided with inwardly-projecting arms, and clamping devices carried by the arms and adapted to engage the raceway.

4. The combination with a pool-table, brackets secured to the table at points between the pockets, a track or raceway secured to the brackets and provided with an extension adapted to serve as a support for the balls, supporting devices each comprising a substantially cylindrical-shaped body portion the upper end of which is extended within the adjacent pocket and the lower end thereof provided with inwardly-projecting perforated arms, and clamping-screws passing through the perforations in said arms for engagement with the raceway.

In testimony that I claim the foregoing as my own I have hereto affixed my signature in the presence of two witnesses.

PAUL MASCHER.
